(57) **CLAIM**

The ornamental design for a detachable clamp for exercise equipment, as shown and described.

DESCRIPTION

FIG. 1 is a right-side view of the detachable clamp for exercise equipment thereof;

FIG. 2 is a left-side view thereof;

FIG. 3 is a front view thereof;

FIG. 4 is a rear view thereof;

FIG. 5 is a top view thereof;

FIG. 6 is a bottom view thereof;

FIG. 7 is a side view, showing the detachable clamp for exercise equipment in use thereof; and,

FIG. 8 is a top view, showing the detachable clamp for exercise equipment in use thereof.

The broken lines show portions of the detachable clamp for exercise equipment that form no part of the claimed design. The additional broken lines in FIGS. 7-8 show environment and form no part of the claimed design.

1 Claim, 5 Drawing Sheets
